UNITED STATES PATENT OFFICE

RICHARD GROETCHEN, OF CHICAGO, ILLINOIS

LAP

Application filed April 18, 1927, Serial No. 184,566. Renewed November 14, 1929.

This invention relates to a smoothing, lapping or polishing process and to an apparatus for carrying out such process. It has for one object to provide a lap, the major portion of which is permanent and in which the part subjected to abrasion and wear is removable. Another object is to provide a lap which will automatically accommodate itself in lapping to holes of a relatively wide variation in size. Another object is to provide a process whereby a constantly moving and shifting layer of abrasive is brought up to carry out the lapping operation. Other objects will appear from time to time in the course of the specification and claims.

The invention is illustrated more or less diagrammatically in the accompanying drawings, wherein—

Figure 1 is a vertical cross-section of a piece during the lapping operation showing the lap and associated parts in elevation.

Figure 2 is a perspective view of the permanent portion of the lapping device with the wearing part removed.

Figure 3 is a perspective of the wearing part of the lap.

Figure 4 is a transverse cross-section taken on line 4—4 of Figure 1 and on an enlarged scale.

Figure 5 is a view similar to Figure 4 in which the wearing part has been reversed in relation to the permanent part of the lap.

Figure 6 is a view similar to Figure 3, showing a modified form of the wearing member.

Like parts are indicated by like characters throughout the specification and drawings.

A is a piece in which a perforation A¹ has been formed.

B is any suitable rotating device in which the lap C is removably positioned.

The lap consists of a main shank portion C which may have a reduced upper end C¹ and which normally has formed about it an outwardly extending flange or ring C². It

is provided in its outer or lower end with a slot C³, and preferably at the inner end of the slot it has an enlargement C⁴. It is also provided with a plurality of circumferential slots C⁵ evenly spaced therealong.

D is a wearing member or part formed in a generally cylindrical shape, provided with an inwardly bent flange or edge D¹, which is circular with the axis of the member D. The member D is preferably so proportioned that when it is positioned upon the outer or lower end of the lap C with the tongue or flange D¹ lying within the slot C³, its free edge will not meet the point X at which the flange D¹ is inwardly turned and there is thus left a narrow slot or groove like portion X¹. The member D is provided with a plurality of apertures D⁵ arranged in rows and positioned to overlie the circumferential grooves C⁵ of the member C. The location of said grooves and apertures in relation to the members C and D is such that the member D is reversible and that it is impossible to put it on the member C and thrust it against the flange C² without causing the apertures D⁵ to overlie the grooves C⁵. When the tool is in use, an abrasive or preferably a lubricant is applied to it, being inserted into the slot and this works down into the space X¹ and forms a vertical strip of abrasive material extending throughout the length of the member D. It also passes about the grooves C⁵ and through the apertures D⁵, thus insuring a constant and uniform distribution of the abrasive or lubricant throughout the surface of the member D. In the modified form shown in Figure 6, a wearing element is used in which the abrasive material forms a part of the wearing element and thus in effect, the wearing element is impregnated with abrasive and forms in itself an abrasive element. This element may be used with or without additional abrasive.

Referring to Figure 6 I illustrate the member D as imperforate, since under certain

conditions I may not wish to provide it with such perforations.

Although I have shown an operative device, still it will be obvious that many changes might be made in size, shape, and arrangement of parts without departing materially from the spirit of my invention, and I wish, therefore, that my showing be taken as in a sense diagrammatic.

10. The use and operation of my invention are as follows:

When it is desired to smooth or lap the interior of a circular opening, a tool such as that shown, of suitable size is provided and 15 the wearing part is positioned about it. This composite part is then inserted in the hole to be treated. A lubricant is applied, being most conveniently inserted through the enlargement at the inner end of the slot, and 20 with this abrasive preferably in the form of powder, is normally also applied although either may be used alone. The lap is then set in rotation and the materials work downward along the slot and outward into the area 25 X¹ and form an axially extending abrasive strip or zone which carries out the lapping effect as the part is rotated. It also passes about the grooves C² and through the apertures D³, being thus distributed throughout 30 the surface of the member D. Under normal conditions rotation is in the direction of the arrow shown in Figure 4. Where the tool is somewhat too small for the hole or for other reasons, it is sometimes desirable to 35 reverse the rotation of the part. When the part is rotated in the direction of the arrow, the rotation tends to cause the free edge of the member D to approach the edge X. When the rotation is in the reverse direction, it tends to force the free edge of the member D away from the edge X and thus in effect to swell or enlarge the size of the 40 wearing element and so to carry out more completely the lapping effect. During these operations, the abrasive normally finds its way to all parts of the exterior of the wearing element D but it is collected in the greatest quantity on the zone X.

Claims:

50. 1. In a lapping device, a main part, including a cylindrical portion, an auxiliary part, mounted thereon, including a perforated cylindrical shell, the main part being provided with circumferential grooves in 55 line with said apertures and a longitudinal groove in communication with said circumferential grooves.

55. 2. In a lapping member, a main part having a slotted end and an outwardly extending flange, an auxiliary part adapted to be removably fitted about such slotted end to contact said flange, such auxiliary part having an inwardly extending member penetrating such slot, the main part being formed with a 60 plurality of circumferential grooves, the

auxiliary member being provided with a plurality of apertures adapted to overlie said grooves.

3. In a lapping device, a driving member constituting a mandrel and provided with 70 surface depressions, a split metallic sleeve constituting an operating member removably mounted thereon, that portion of the sleeve overlying the surface depressions of the mandrel being perforated, cooperative 75 means formed on the sleeve and mandrel for securing one end of the sleeve against movement circumferentially of the mandrel, there being a longitudinal duct formed in the mandrel communicating with the surface depressions thereof, said sleeve embracing the mandrel circumferentially with its opposite end free and movable circumferentially of the mandrel to expand the operating member when the mandrel is rotated 80 in a direction in which the free end of the sleeve leads the secured end thereof.

4. In a lapping device, a driving member constituting a mandrel and provided with 85 surface depressions, a split metallic sleeve 90 constituting an operating member removably mounted on the mandrel, that portion of the sleeve overlying the surface depressions of the mandrel being perforated, the sleeve and mandrel being formed with interfitting parts 95 preventing relative rotation of the sleeve and mandrel, there being a longitudinal duct formed in the mandrel and communicating with the surface depressions; said sleeve having one of its ends free and adapted when 100 the lapping device is rotated in one direction to hug the mandrel more closely and when rotated in the opposite direction to tend to move outwardly away from the mandrel to expand the sleeve.

5. In a lapping device, a driving member constituting a mandrel, a flexible metallic sleeve having a flange thereon, said driving member being provided with a plurality of 105 surface depressions and having a passage formed therein communicating with said depressions, said flange being engaged in the passage whereby the sleeve is held against rotation with respect to the driving member, said sleeve extending about the driving 110 mandrel throughout the major portion of the periphery thereof and being provided with perforations communicating with the surface depressions of the driving member, one end of the sleeve being free to permit relative 115 movement thereof with reference to the mandrel.

6. In a lapping device, a driving member constituting a mandrel and provided with 120 surface depressions, a split metallic sleeve 125 constituting an operating member removably mounted thereon, that portion of the sleeve overlying the surface depressions of the mandrel being perforated, said sleeve and mandrel being formed with interfitting parts 130

5 preventing relative rotation of the sleeve and mandrel, said sleeve embracing the mandrel circumferentially with the opposite ends of the split sleeve terminating in spaced relation, one of said ends being free to permit relative movement thereof with reference to the mandrel.

Signed at Chicago, county of Cook, and State of Illinois, this 15th day of April, 1927.
